PRICE TAG FOR WATCHES OR THE LIKE

Alexander M. Fekula, Cincinnati, Ohio, assignor to The Gruen Watch Company, Cincinnati, Ohio, a corporation of Ohio

Application March 25, 1954, Serial No. 418,715

2 Claims. (Cl. 40—2)

This invention relates to price tags and is particularly concerned with a tag of the type which is adapted to be inserted in a preformed slit in a watch or jewelry box having a hinged lid so that in window or counter displays prospective purchasers can readily examine the merchandise and simultaneously consider the price thereof without removing the box from the display.

In the use of price tags in conjunction with articles conventionally sold in boxes having hinged lids such as watches, jewelry or the like, it has been the practice for some time to provide a preformed slit in the upper surface of one of the lower side walls. Into such a slit is inserted a relatively rigid tag usually of generally rectangular configuration on which the price of the merchandise is printed or otherwise indicated.

Little care or thought has been given to the construction of the tags used and in the case of the conventional flat rectangular tags a number of objections have developed. Since the inserted tags are supported only by frictional line contact they have a tendency to tilt forward or backward, in many cases obscuring the price marking and at the least providing a sloppy display. Occasionally the tags become inserted too far into the slit which also obscure the price marking and it even happens that they are sometimes pushed all the way through the slit into the body of the box. Conversely if the tags are not pushed into the slit far enough they are apt to become disengaged and to lie flat on the bottom of the box which also obscures the view of the price marking and detracts from the appearance of the display.

With a view to correcting the aforesaid difficulties I have provided an improved tag for the purpose described which is so constructed that it will always remain in a rigid upright position. Once the tag has been inserted in the slit there is no possibility that it can be pushed entirely through into the body of the box and practically no possibility that it can become dislodged from the slit. A display of boxes with the improved tags inserted therein will accordingly provide a much neater and more attractive appearance than those utilizing tags of the present conventional type.

Referring now to the drawings in which there is illustrated a preferred embodiment of my invention;

Figure 1 is a perspective view of a watch display box of the conventional type with the tag of the invention about to be inserted in a preformed slit in the upper base surface of one of the lower side walls.

Figure 2 is a perspective view similar to Figure 1 with the tag fully inserted in the preformed slit.

Figure 3 is a plan view of the tag alone.

Figure 4 is a sectional view along the line 4—4 Figure 3.

Figure 5 is a sectional view along the line 5—5 Figure 3.

Figure 6 is a diagrammatic view showing the tag about to be inserted in a preformed slit.

Figure 7 is a similar view showing the tag when it is almost fully inserted.

2

Figure 8 is a similar view showing the tag fully inserted.

As illustrated in Figure 1 the tag of the invention designated generally as 10 is about to be inserted in a preformed slit 11 in the upper surface of one of the lower side walls of a box designated generally as 12. The tag itself may be formed of cardboard or the like includes the elements of a relatively short transverse panel 13 on which the price marking indicia is adapted to be placed. This panel is in all instances wider than the width of the preformed slot 11, thereby preventing the tag from being inserted all of the way through the slot into the body of the box. An insertion tab 14 is formed integrally with the panel 13 and depends therefrom. Extending vertically across this insertion tab are a plurality of wedge shaped channels or bosses 15. These channels extend from the lower edge of the tab to a point very slightly below the juncture of the tab and the panel, and as illustrated in Figure 4, beginning at the lower end of the tag 16 they become increasingly deep as they extend upwardly on the tab, thereby providing what is in effect a series of wedges, which because they are deeper than the width of the slit have a tendency to spread the edges of the slit and provide a secure interlock between the tag and the box.

As illustrated in Figure 7, particularly, when the tag is almost fully inserted and the deepest portion 17 of the channel is engaged with the slit the tag will be held in perfectly upright position. As the insertion is continued as illustrated in Figure 8, an interlock is provided which effectively prevents the easy withdrawal of the tag. The degree of insertion illustrated in Figure 8 or that illustrated in Figure 7 are equally effective for commercial purposes. That illustrated in Figure 7 provides a tighter engagement and tends better to maintain the tag in erect position. That illustrated in Figure 8 has the additional advantage of the interlock.

From the foregoing it will be apparent that a simple but effective improvement has been provided in tags of the type under consideration.

Having fully described my invention I claim:

1. A marker tag for use with a display box having a preformed slot in a thin wall thereof, comprising: an upper panel member of greater length than said slot; an insertion tab depending from said panel member; a plurality of vertically extending bosses integral with and formed in said tab, said bosses extending from the lower edge of the tab upwardly to a point spaced slightly below the line of juncture of the panel and the tab, the bosses extending a greater distance outwardly away from the tab at their upper ends than at their lower ends, the upper edges of said bosses being uniformly spaced below said line of juncture at a distance approximately equal to the thickness of said wall, whereby when said tab is fully inserted into the slot an interlock between the wall and said tag is obtained.

2. The marker tag of claim 1, wherein each of said bosses, at its upper end, and commencing at its point of greatest spacing from the plane of the tab, is progressively declined upwardly towards the tab to form a short wedge-shaped portion, whereby when said marker tag is withdrawn from said slot, said wedge-shaped portion on said bosses serve to slightly displace the walls of said slot and allow the widest portion of the bosses to pass therethrough.
